FRANK R. EVANS, OF ZANESVILLE, OHIO.

METHOD OF AND APPLIANCE FOR ERECTING BUILDING WALLS.

Application filed November 22, 1923. Serial No. 676,440.

This invention relates to a novel method of and appliances for erecting building walls and similar structures.

It has been the custom heretofore to erect brick building walls by laying the outer courses of bricks which are to constitute the facing courses of the wall, and back these courses up by laying backing courses in rear thereof. Both of these operations have been performed solely by hand and it is a well recognized fact that considerable skill is required on the part of a brick layer to lay the courses which comprise the wall. This is particularly true of the facing courses for they must be laid with exceptional care in order that the outer surface of the wall may be plane and likewise in order that the wall may be plumb. While less care and skill is required in laying the backing courses, nevertheless this is a time-consuming task and an item of expense, both for labor and material. After such a wall has been erected, it is necessary to plaster the same and this too requires experience and involves expense. While as stated, the same degree of care and skill is not required to be exercised in laying the backing courses of the wall, nevertheless, this may be done with sufficient care to render the inner face of the wall sufficiently smooth to permit of the plastering operation being properly performed. Another well known and popular method of erecting a building wall is to lay the facing courses of bricks and back up the facing wall with building tile, but in this method as in the preceding one, experienced bricklayers must be employed if the work is to be performed in a satisfactory manner. In both of these common methods, exceptional skill must be employed in erecting the corners of the structure in order that the same may be precisely plumb, any deviation from the perpendicular at these portions of a building structure being very noticeable whereas slight deviations from a plane surface at one or more portions of the intermediate area of a building wall may not be so noticeable. It is for this reason that in erecting a building, the more experienced bricklayers are selected to lay the corner courses of the facing wall and even to lay the backing courses at this portion of the structure. Very naturally the em-

ployment of skilled labor adds materially to the cost of erection of the structure. In 55 consideration of the foregoing, it is the primary object of the present invention to evolve a method of and appliances for erecting building walls, by carrying out which method and employing which appliances, even the most unskilled workmen may be employed and, by their labors, erect a wall which will be precisely plumb and the facing surface of which will be plane throughout its entire area, the nature of the invention being such that in following the method and employing the appliances, a building wall may be erected in a fraction of the time which would be required under the employment of skilled laborers and following the 70 ordinary methods.

In backing up facing wall courses, and by the old method in which the backing is done by laying the backing course of brick or tile, the cost of the material is considerable even though an inferior quality of bricks be employed for the backing courses, in the former instance, and it is therefore another important object of the invention to evolve a method whereby the backing of 75 the facing wall may be effected at a much lower cost both for material and for labor and at the same time a much more substantial and durable wall be produced.

As previously pointed out, in erecting a 80 building wall by the methods now in common use, the greatest skill must be exercised in laying the corner courses. Therefore it is another very important object of the present invention to provide means whereby 85 these courses may be laid with great accuracy by unskilled workmen so that not only may the contractor avoid the expense of employing skilled labor but the further advantage is gained that by the use of the 90 present invention the corners of the structure may be erected with much greater accuracy than where skilled labor is employed under the old methods.

The ordinary methods of erecting brick or 100 other walls present another disadvantage, namely that scaffolding must be erected on which the workmen may stand while laying the courses and upon which the bricks and mortar may be supported for their use. 105 Wood is the material commonly employed

in erecting such scaffolds, and after the wall has been erected, the scaffolding must be torn down. In consequence of the tearing down of the scaffolding, considerable material is wasted or damaged so as to be unfit for further similar use, and therefore the salvage is not considerable and the loss thus sustained must be added to the cost of erecting the wall. Therefore, it is another important object of the invention to provide a temporary structure which will serve all of the purposes of the ordinary scaffolding in the process of building the wall and which will present a decided advantage over the ordinary temporary scaffolding, namely that practically every member or device employed in the construction of the same may be recovered after the wall has been erected and employed time after time in future operations, so that by the present invention there is saved, to the builder, the expense incident to the erection and salvage of the ordinary wood scaffolding.

As regards the temporary structure referred to above, it is another object of the invention to provide therein a novel platform support, means for supporting the same, and means whereby the supporting means may be elevated in a most convenient manner as the building operation progresses so that there is no necessity for interrupting the work of the bricklayers, as in the old methods, while carpenters add to the wooden scaffold structure.

As before pointed out, and as has been demonstrated by the actual erection of a building structure, in accordance with the principles of the present invention, the invention contemplates that this work be rendered capable of accomplishment by the most unskilled workmen with an exceptional degree of accuracy and with this end in view the invention embodies, as another important feature, means adapted to be elevated from time to time during the building operation, and constituting a brick laying guide against which the workmen may dispose the bricks to be laid, with assurance that when properly disposed against the guide and mortar applied in the usual manner, the courses will be accurately and correctly located. In this manner, and by this means, the necessity of applying plumb and level to the wall during the course of erection thereof is entirely obviated and much time is saved and the work is performed in a more accurate manner and more expeditiously.

It is now generally recognized that concrete constitutes an excellent building material but it has likewise been found that it alone cannot be employed in the erection of building walls. The material absorbs moisture and, due to atmospheric changes, is subject to cracking and disintegration.

Therefore, notwithstanding its otherwise substantial and durable qualities, its use as a material, alone, in the construction of building walls, has been practically abandoned. Of course, if a building wall could be constructed of this material and protected from the elements, a durable and substantial structure would be the result. However, so far as I am aware, this has not been accomplished prior to my invention. Therefore the present invention has as a further important object to provide means whereby a wall may be erected comprising a facing wall of brick or other facing material and a backing wall of concrete so that the wall structure as a whole will be more substantial and durable than a brick or tile backed wall, and a saving in the cost of materials will be effected. In this connection the invention contemplates erecting the wall in such a manner that an intimate bond will be formed between the facing courses and the backing of the wall, the backing giving added strength to the wall, and the brick facing, being of a vitreous nature, will so protect the concrete backing as to exclude moisture therefrom, thereby eliminating the factors which ordinarily cause cracking and disintegration of concrete.

Another important object of the invention, so far as regards the construction of a building wall from brick and a concrete backing, is to evolve a method whereby the bricks may be laid and the backing poured in such a manner as to not only effect union between the two sections of the wall, but likewise in such a manner that the brick facing section will constitute one wall of the mold in to which the concrete backing is poured so that, unlike the methods followed in building a wall of concrete alone, there is no necessity of constructing a complete mold or form for this purpose. In this connection, the invention has as a further object to provide an adjustable mold wall member and means for supporting the same in such a manner as to permit of elevation of the said member at successive periods in the building operation.

Still another object of the invention is to so construct the mold wall member that by its use, the backing section of the building wall, will, at the time of its completion, present a smooth and unbroken surface in which no joints or seams will appear and which surface may be finished in any of the well-known ways.

Another object of the invention is to so construct the temporary structure employed in carrying out the method, that its component parts may be adjusted and arranged in various ways so as to provide for offsets and various other structural deviations from a straight or plane wall, as occasion may require during the process of erection.

In the accompanying drawings:—

Figure 1 is a perspective view illustrating the initial steps in the method of constructing a building in accordance with the principles of the present invention;

Figure 2 is a view partly in elevation and partly in section illustrating the appliances or apparatus employed in carrying out the method and likewise illustrating several succeeding steps in the method;

Figure 3 is a detail horizontal sectional view taken substantially on the line 3—3 of Figure 2 looking in the direction indicated by the arrows;

Figure 4 is a detail view partly in elevation and partly in section illustrating the brick laying guide of the invention, the parts being shown in the position which they will assume during the brick laying operation;

Figure 5 is a similar view illustrating the positions assumed by the parts when it is desired to point the course or courses of bricks which have been laid;

Figure 6 is a view in front elevation of the brick laying guide structure;

Figure 7 is a perspective view illustrating component parts of the said structure disassembled;

Figure 8 is a detail vertical transverse sectional view on the line 8—8 of Figure 4;

Figure 9 is a perspective view illustrating one form of attaching means for the brackets of the brick laying guide;

Figure 10 is a fragmentary view in elevation of one of the rack bars which constitutes a supporting means for the brick laying guide;

Figure 11 is a fragmentary perspective view in detail illustrating means provided for slightly displacing the mold wall member to permit of its vertical adjustment without disturbing the concrete backing which has been poured;

Figure 12 is a vertical sectional view, parts being shown in elevation, illustrating the manner of carrying out the invention in cases where the facing wall is to be backed by tile;

Figure 13 is a similar view illustrating the manner of carrying out the invention where the facing wall is to be backed by brick;

Figure 14 is a similar view illustrating another way in which the invention can be practiced.

Figure 1 of the drawings illustrates in a general way the first steps which are to be carried out in erecting the walls of a building structure by the method of the present invention. In carrying out the method, the first step consists in digging an excavation, E, on the site where the building structure is to be erected, the contour and dimensions of this excavation corresponding to the

exterior contour and dimensions of the foundation of the said building structure. In the bottom of the excavation there is then dug a trench indicated by the reference letter T which trench extends around the 70 sides and ends of the excavation. Concrete is then poured into the trench and, when it sets, forms the footing 1 of the foundation of the building structure, the footing being preferably flush with the bottom surface of

the excavation E as illustrated in the said Figure 1. After pouring the concrete which is to form the footing 1, and before the concrete has set or hardened, a number of bolts 2 are embedded in the concrete with their 75 threaded shanks projecting upwardly.

These bolts will be of a number and arranged in such a manner as will be determined by the dimensions of the building structure and the contour thereof. As a 80 simple illustration of the invention, the building to be erected upon the foundation illustrated in Figure 1 will be of oblong rectangular form and of a relatively small size, and in this particular instance it will 85 be found advisable to locate one of the bolts 2 at each corner of the foundation, and a pair of the bolts between each two corners of the foundation at each of the longer sides thereof and preferably midway between the 90 said corners. This arrangement, however, is

purely an arbitrary one and it will be understood that it is merely illustrative of one application of the invention and that the arrangement may be variously modified depending upon circumstances. The appliances employed in carrying out the method of the invention are supported upon a skeleton frame structure which comprises up- 95

rights indicated in the drawings by the numerals 3 and 4. The uprights 3 are preferably of angle iron of L-form in cross section, and the uprights 4 are preferably of T-form. Foot brackets 5 are secured to the 100 lower ends of the uprights 3 and are fitted to the projecting threaded shanks of the bolts 2 at the corners of the foundation. Similar foot brackets 6 are secured to the lower ends of the uprights 4 and engage the

respective pairs of bolts at the longer sides 105 of the foundation and are secured in place by nuts. The uprights having been arranged in the manner illustrated and described and having been firmly and securely united to the footing 1 of the foundation, the sev-

eral uprights are connected and relatively braced by any suitable means, such, for example, as tie wires 7 which may be tensioned by turn buckles 8, and likewise by 110

guy wires 9 which may be tensioned by turn buckles 10, the guy wires 9 extending downwardly from the uprights to stakes or other anchoring devices 11 located outwardly beyond the walls of the excavation E.

In mounting the uprights in place and 115

securing them to the foundation, the uprights 3 are secured to the foot brackets 5 and the uprights 4 are secured to the foot brackets 6, the nuts being tightened to hold the uprights in place.

After the uprights are secured in place, the tie wires 7 and guy wires 9 are tensioned to hold the uprights in place and to hold the uprights in place.

After the tie wires 7 and guy wires 9 are tensioned, the uprights are secured to the foundation by nuts.

After the uprights are secured to the foundation by nuts, the tie wires 7 and guy wires 9 are tensioned to hold the uprights in place and to hold the uprights in place.

in adjusting the tie and guy wires, care is taken so that when all adjustments have been made, the uprights will each assume a true perpendicular position. The wings of the angle iron uprights 3 and 4 are formed with openings 12, the purpose of which will presently be explained, these openings extending in a longitudinal series along each wing as clearly shown in Figure 1.

10 The first one of the devices which is brought into use, in carrying out the method beyond the step above recited, is a mold member which is indicated in general by the numeral 13. This device comprises a 15 mold wall member 14 which may, as illustrated most clearly in Figure 2 of the drawings, be in the form of a channel-iron beam of a suitable length and embodying upper and lower flanges 15 and 16 and a connecting web 17. At its ends, the mold wall member 14 has its flanges 15 and 16 cut away or recessed, as indicated by the numerals 18 and 19, respectively, so as to adapt the ends of the said member for disposal against the 20 outer sides of the uprights of the skeleton frame structure heretofore described. One of the members 14 may be arranged to extend between two of the uprights 3 and transversely of one or the other of the ends 25 of the skeleton frame structure, and likewise the same or other corresponding members 14 may be disposed to extend between any of the uprights 3 and the next adjacent upright 4. In any event the recesses 18 and 30 19 in the flanges 15 and 16 will be so formed that when the member 14 is properly arranged against two of the uprights as, for example, two of the uprights 3, the outer face of the web 17 of the said member will occupy a vertical plane, and this face of the member will be finished smooth. The numeral 20 indicates in general rack bars which constitute supporting means for the mold wall member 14. Each of the rack bars is provided longitudinally of one edge 35 with a series of teeth 21, and each bar is provided at points in its length as, for example, adjacent each end and at opposite sides of and relatively close to a point midway between its ends, with bosses 22 which are formed upon one face thereof. The bars are likewise formed, at the points of location of the bosses, with openings 23 which are in alignment with the openings in the bosses, and bolts 24 are adapted to be fitted through the openings 12 in the wings or flanges of the angle iron uprights and through the said openings 23 and have nuts 25 fitted on their ends and bearing against the respective rack bar, the bolts and nuts serving to secure the rack bar to the angle iron uprights, and the bosses 22 serving to space the rack bars a short distance from the plane of the inner side of the wing of the angle iron to which it is secured. In order that the mold wall

member 14 may be supported by the rack bars upon two adjacent ones of the uprights of the skeleton frame structure, rockers 26 are pivotally mounted, as at 27, upon the web portion 17 of the said member 14 near 70 the ends thereof, and idle pawls 28 are mounted upon the pivots 27 for the said rockers 26 and are yieldably held by springs 29, in engagement with the teeth of the adjacent or respective rack bars 20. A pawl 75 30 is mounted upon the end of one arm of each rocker 26 and is yieldably held by a spring 31 in engagement with the teeth of the respective rack bar 20, and rods 32 are pivotally connected with the other arms of the two rockers 26 and likewise pivotally connected to the arms 33 of an operating lever 34 which is mounted for oscillation, as at 35, upon the member 14. The engagement of the pawls with the teeth of the rack bars serves of course to support the member 14 in position upon the uprights 3 or 4 and 4 as the case may be and it will be evident that upon oscillating the lever 34, the rockers 26 will be so oscillated as to cause the pawls 30 and 28 to alternately ride over and engage above the respective teeth upon the opposing edges of the rack bars, this constituting means whereby the member 14 may be elevated from time to time as the building 95 operation progresses. In order that the member 14 may be maintained in proper relation to the uprights of the skeleton frame structure and yet have a slight freedom of play which will presently be explained, small 100 clips 36 are bolted or otherwise removably secured upon the web 17 of the member 14 and loosely engage over the margins of the flanges of the angle iron uprights against which the ends of the said member 14 are 105 disposed.

Having arranged one or more of the members 14 in proper position upon the uprights, the said member or members occupying a position at the extreme lower end of the uprights, concrete is poured into the space between the smooth finished faces of the said members 14 and the wall of the excavation E until the concrete is substantially 110 level with the upper flange 15 of the said member 14. When the concrete has partially set, the lever 34 is operated so as to bodily elevate the member 14 until the lower flange 16 thereof occupies a plane slightly below the plane of the surface of the 115 poured concrete mass, and this operation is repeated until the main foundation, which is indicated in the drawings by the numeral 37, has been completely formed, this foundation being formed, of course, directly upon the 120 footing 1 thereof and as illustrated in Figure 2. The main foundation will, of course, extend, in that embodiment of the invention illustrated in Figure 2, substantially to the 125 ground surface, and from this point through 130

out the remaining steps of the method, the procedure is somewhat different from that just described. At this point it may be explained that the pouring operation is more or less a continuous one; that is to say, the mold space between the mold member 14 and the wall of the excavation at one end of the excavation may, for example, be filled by poured concrete, and the concrete mass be permitted to remain confined within the mold chamber provided by the said wall of the excavation, the member 14, and the footing 1, assuming that the building of the main foundation 37 has just been begun, and then the workmen may proceed along one side of the excavation, thence along the other end thereof, and finally along the other side of the excavation. By this time, ordinarily, it will be found that the first poured concrete has set sufficiently to permit of upward adjustment of the mold member 14 so that the pouring operation may be again begun at the first mentioned end of the excavation and continued as before until the entire main foundation 37 has been completed. This method of procedure could, of course, be followed, with advantage, by a single workman, while on the other hand if a number of workmen were employed on the building, they might be so arranged along the sides and ends of the excavation as to permit of all sides and ends being poured simultaneously. The manner of procedure in carrying out this step of the method may be left more or less to the judgment of the workmen or contractor and will, of course, depend more or less upon the number of workmen employed and the size of the building structure.

The mold members 14 are adjusted upwardly while the concrete mass molded thereby is still in a semi-plastic state, and in order to prevent any distortion of the surface of the mass due to sliding frictional contact of the smooth face of the member 14 therewith, means is provided which will now be described. The numeral 38 indicates rods which are pivotally connected at relatively adjacent ends to the arms 39 of an operating lever 40 pivotally mounted, as at 41, upon the web 17 of each member 14, and the opposite or outer ends of the rods are provided with wedges 42 which ride against inclined portions 43 formed upon the inner sides of the web portion 17, the wedges 42 entering between the said faces 43 and the outer sides of the respective uprights of the skeleton frame structure against which the member 14 is disposed. The wedges 42 are located immediately above the lower flanges 16 and below the clips 36. In practice, the lever 40 will be rocked about its pivot so as to exert endwise thrust against the rods 38 and thus slide the wedges 42 into position between the inclined faces 43 and the said outer faces of the uprights of the skeleton frame, prior to the pouring of the concrete. After the concrete has been poured and immediately prior to adjusting the member 14 upwardly to position where a further pouring may take place, the said lever 40 is manipulated so as to pull upon the rods 38 and slide the wedges 42 inwardly, thereby permitting the member 14 to have a slight tilting movement so that it will, at its lower portion, recede from the face of the poured mass of concrete just sufficient to prevent this portion of the member 14 exerting any appreciable pressure against the face of the concrete mass. Should the member 14 be immediately shifted upwardly, the frictional contact of its smooth finished face with the semi-plastic concrete might tend to exert a pull upon the mass and distort the same. This may be avoided by moving the member 14 downwardly a short distance immediately prior to shifting it upwardly so as to thereby overcome to a greater or less degree the adherence of the concrete to the face of the said member, and this is effected by mounting a hand operated rocker 41 upon the member 14 and extending rods or wires 42 from the ends of this rocker to the pawls 28 so that when the rocker is manually turned in one direction, the pawls will be retracted from engagement with the different racks 20 and the lever 34 may then be manipulated so as to permit the member 14 to lower a short distance as, for example, the length of one of the rack teeth, after which the rocker 41 may be released and the springs 29 will return the pawls 28 to position coacting with the respective racks, and the lever 34 may then be actuated to elevate the said member 14, and the pouring operation resumed. As some difficulty may at times be experienced in forcing the wedges 42 into place by operation of the lever 40, due to the pressure of the concrete against the member 14, it is preferable that the ends of the rods 38 be extended somewhat beyond the pivots which connect them with the arms 39 of the said lever 40 and that these projecting ends be formed with relatively blunt heads 44 against which hammer blows may be struck for the purpose stated.

The foundation having been completed, the building of the wall proper is next to receive attention. The wall proper, in the embodiment of the invention now being described, comprises a facing wall section 45 made up of a number of courses of bricks 46, and it likewise comprises a backing section which is indicated by the numeral 47 and which is of poured concrete. Having reached substantially the level of the ground surface or, more specifically, the foundation 37, the mold member 14 is positioned as before and with its lower portion engaging behind the face of the foundation near the

6

top thereof. There is then brought into use the brick laying guide which has heretofore been referred to and which will now be specifically described. The brick or facing laying guide is indicated in general by the numeral 48 and is best illustrated in Figures 2, 4, 5 and 6 of the drawings. For the purpose of mounting the guide, brackets indicated in general by the numeral 49, are provided, and each of these brackets comprises an attaching base 50 and an arm 51 which extend from the lower side of the base, horizontally, and is braced with respect thereto by a connecting brace portion 52. The base 50 of each bracket 49 is designed to be supported upon one of the uprights 3 or one of the uprights 4 as occasion may require, and where the bracket is to be supported upon uprights 3, clamps, indicated in general by the numeral 53, are associated with the attaching base 50 of the bracket. Each of these clamps comprises a member 54 having right angularly extending portions 55 and 56, the former being provided with bolt openings and disposed against the rear side of the attaching base of the bracket to be supported. The portion 56 of the clamp member is provided with a hooked terminal 57 designed to engage behind the free edge of one flange of the angle iron 3 in the manner best shown in Figure 9 of the drawings. The other member of the clamp is indicated by the numeral 58 and the same comprises a portion 59 which is likewise provided with elongated bolt openings or slots and which is disposed in overlapped relation to the portion 55 of the member 54, bolts 60 being secured through these overlapping parts. The portion 59 of the member 58 is provided with a hooked end 61 which is designed to engage over the free edge of the other flange of the angle iron upright 3 as illustrated in the said Figure 9, and after the clamp members have been properly adjusted, the bolts 60 are tightened thereby rendering them rigid with relation to each other. In this manner the entire bracket is slidably supported upon the angle iron for vertical adjustment. Where a T-iron 4 is encountered such, for example, as the iron 4, a clamp of the form illustrated in Figure 7 is employed. This clamp, which is indicated in general by the numeral 62 comprises a pair of substantially counter-part clamping members 63 which are disposed in overlapping relation as in the case of the clamp members 54 and 58, each member being provided with a hooked outer end 64 and the members being relatively adjustable and adapted to be secured to the attaching base 50 of the respective brackets 49 by the tightening of bolts 65 corresponding to the bolts 60 previously described. The hooked ends of the clamp members are designed to engage the free edges of the flanges of the

uprights 3 and 4 and it will be evident, and particularly by reference to Figures 4 and 5 of the drawings, that free sliding movement of the brackets along the uprights will not be interfered with by the rack bars 29 inasmuch as these bars are, as previously stated, spaced from the said flanges of the uprights. The arm 51 of each bracket 49 is formed with a longitudinal slot 66, and at its upper and lower sides the arm is provided at its opposite faces with series of teeth or serrations 67. The arm of each bracket is formed as just described where the bracket is to be employed upon one of the uprights 4, but where the bracket is to be employed upon one of the corner uprights 3, the teeth 67 at one side or face of the arm may be omitted if desired although it may be found equally expedient to form all of the brackets of counterpart construction and employ them indiscriminately. The brick laying guide is suspended between bearing members upon associated ones of the brackets 49, and each of these bearing members, indicated in general by the numeral 68, comprises a body 69 which is of substantially segmental form and which is provided upon one face parallel to its upper straight edge, with a longitudinal rib 70 which is seated between the toothed flanges 67 of the bracket arm 51, the body being in this manner supported for longitudinal adjustment upon the said arm 51. The said face of the body 69 above and below the rib 70 is formed with a series of teeth or serrations 71 which coact with the teeth or serrations 67 upon the arm 51 so as to prevent displacement of the body 69 after it has been moved to the desired position of adjustment. At the juncture of the two straight sides of the body 69 or in other words at the upper inner corner of the said body, the body is provided with a short extension 72 which terminates in a bearing collar 73. At this point it will be understood that where one of the brackets is mounted upon one of the corner posts 3, a single one of the bearing members 68 will be associated therewith but that where the bracket is mounted upon one of the intermediate uprights 4, two of the bearing members will be associated with the bracket as shown for example in Figure 8 of the drawings. It will be observed by reference to said figure that the bearing collar 73 has its opening 74 in alignment with the slot 66 in the bracket arm 51. A bushing sleeve 75 is fitted through the opening 74 and through the slot 66, and a double ended bolt 76 is fitted through the bushing sleeve 75 and has nuts 77 threaded onto its ends and bearing against washers 78 which in turn bear against the ends of the said bushing sleeve 75. The brick laying guide which is indicated in general by the numeral 79 includes

hangers 80 which at their upper ends are provided with openings 81 of a diameter to receive the ends of the sleeve 75, the hangers being positioned between the outer side of the collar 73 and the washer 78 and being in this manner suspended for pivotal or swinging movement as will be readily understood. At this point it will be evident that by loosening one of the nuts 77, the bearing member 68 may be laterally displaced so as to permit the serrations or teeth 71 clearing the teeth 67 whereupon the said bearing member may be slidably adjusted along the bracket arm 51 until the suspended brick laying guide 79 has been adjusted to the proper distance from the plane of the building wall being erected, in the event an offset is to be made in the wall, or until the said member has assumed a position with its working face in the plane of the outer surface of the wall being built. The nut 77 may then be tightened so as to secure the bearing member 68 in place, and the guide will then be suspended in position for use.

The suspension arms 80 of the brick laying guide are preferably located at the ends of an angle iron bar 82 which constitutes in effect a straight edge, the depending or vertically disposed wing of the said bar, indicated by the numeral 83, occupying a vertical plane when the guide is suspended in position for use, and the face of this wing of the bar being plane and constituting an abutment against which the bricks are to be laid in courses. It is preferable that the bar 82 be reinforced by a second angle bar 84 which is disposed within the angle of the bar 82 and riveted or otherwise secured thereto as indicated by the numeral 85. The reinforcing bar 84 will, of course, prevent any sagging of the intermediate portion of the bar 82 so that the upper side of the said bar 82 will occupy a true horizontal or level plane. In other words, the bar 82 will, in the use of the device, serve both as a level and a plumb. It is, of course, essential that the brick laying guide be held against outward swinging movement while in use, and for this purpose a rock lever 86 is mounted upon the upper side of the bar 82, and rods 87 are connected to the said lever at opposite sides of the pivot therefor and at their opposite ends are connected to sliding latches 88 which are mounted in suitable housings 89 upon the suspension arms 80 and which latches, through manipulation of the lever 86, may be projected into engagement with the rear edge of the body 69 of the bearing members 68. The said rear edges of the bearing members of each brick laying guide therefore constitute abutment means for the latches 88 and serve to prevent forward or outward swinging movement of the said guide beyond the perpendicular.

In order to permit of the workmen pointing the bricks as the courses are laid, it is of course essential that the brick laying guide be swung away from the wall and this may be done by operating the lever 86 so as to retract the latches 88 and then so moving the said guide until it assumes substantially the position shown in Figure 5 of the drawings whereupon the lever may be again actuated to project the latches into engagement with the upper sides of the respective bracket arms 51, the engagement of the latches with the said arms then serving to support the guide in the position shown in the said figure and entirely clear of the wall. In order that the brackets 49 may be vertically adjusted upon the uprights 3 and 4 to correspondingly adjust the brick laying guides supported thereby, as the building operation progresses, each bracket is provided with a laterally projecting arm 90 which extends from its attaching base 50 and which supports, at its outer end, a lever 91 pivotally mounted upon a pivot pin 92, at a point between its ends. A pawl 93 is freely supported at the inner end of the lever at one side of the pivot pin 92, and a spring 94 bears against said pawl and holds the same yieldably in engagement with the teeth 21 of the respective rack 20. A pawl 95 is likewise supported upon the pivot pin 92 and is yieldably held by a spring 96, in engagement with the teeth of the respective rack. Thus by operating the lever 91, the corresponding brackets may be shifted upwardly along the upright upon which it is mounted.

The foundation having been laid and completed, the erection of the building wall is continued by first positioning the mold wall member 14 so that the lower portion of its working face will abut against the inner side or face of the said foundation near the top thereof, and the brick laying guide is then so positioned that the face of the depending flange 83 thereof will be substantially opposite the face of the member 14 and at such elevation that bricks may be laid by the workmen against the face of the depending flange of the said member 82, the first course of bricks being laid upon the foundation along the length of the said guide. After the first course has been laid, the guide is elevated through manipulation of the lever 91, until the guide is in position for the laying of the second course whereupon the said course is laid, and this operation is continued until a number of courses have been properly laid, the guide being swung away from the face of the wall at suitable intervals, to permit of the mortar being struck and the wall thus pointed, during the operation. After a predetermined number of courses of the bricks have been laid in the manner recited, concrete is poured.

into the space between the laid courses of bricks and the face of the mold wall member 14, the courses of bricks constituting one wall of the mold and the said member 14 constituting the opposite wall thereof, the foundation previously laid constituting the bottom of the mold and the assemblage of parts then constituting a mold chamber in which the concrete may be permitted to set and partially harden before the member 14 is again elevated to position for a continuation of the pouring operation. At suitable intervals, wall ties 97 may be embedded between the courses of bricks and in the mortar comprising the backing of the wall as clearly shown in Figure 2 of the drawings, and sills, such, for example, as the sill 98, may be embedded in the wall structure wherever desired or where occasion may require. It will be evident that offsets in the wall may be made by adjusting the supports 68 for the brick laying guide outwardly or inwardly along the arms 51 of the brackets 49 and that these offsets may be made with accuracy inasmuch as the adjustment of the bearing members for the brick laying guide may be accurately made and predetermined. It will be understood at this point that any desired number of courses of bricks may be laid preceding the pouring of the concrete backing, that is to say one or two courses may be laid and the concrete immediately poured or the courses may be laid for a height of five or six feet, for example, and the pouring then be effected by adjustment of the mold wall member 14, it being evident, of course, that if desired this member may be built up of a number of angle irons or otherwise made of a depth sufficient to permit of the carrying out of the pouring operation under such conditions. In the course of erecting the wall, bricks may be embedded at the proper level, during the pouring operation, and then removed after the concrete has partly set, so as to provide steps or sockets such, for example, as indicated by the numeral 99 and illustrated in Figure 2 of the drawings, to accommodate the ends of the beams upon which the floor is to be laid. Likewise, at intervals in the course of erection of the wall, sockets will be formed in the semi-plastic concrete by the insertion of plugs or otherwise, and links 100 will be inserted into these sockets and the sockets then filled with clay which, after the wall has set and hardened, may be dug out so as to expose one end of the link to permit of the connection therewith of a tie bolt 101, the outer end of the bolt being fitted through one or another of the openings 12 in the uprights of the skeleton structure whereby the said uprights will be anchored to the wall as the wall is erected. In this manner the uprights are, in the course of erecting the structure,

securely braced with relation to the wall and caused to at all times assume a true perpendicular position which is essential to the carrying out of the method. Of course, after the structure has been erected, the uprights are to be removed as well as the tie bolts 101 so that as a matter of fact the only loss of material is that of the bolts 2 and the links 100, all other parts of the apparatus and skeleton frame structure being capable of being salvaged and again employed.

It will be understood that while the foregoing description has been directed more particularly to the erection of a building wall comprising an outer or facing wall section of bricks and an inner or backing section of concrete, the invention is not restricted to the employment of such materials, but on the other hand, facing and backing materials of various kinds may be employed in carrying out the method. For example, tile might be employed instead of the ordinary facing bricks or the wall may be backed by the employment of building tile as illustrated, for example in Figure 12 of the drawings, in which event the tile will be faced by pouring the concrete or other aggregate to provide a facing for the inner surface of the wall, the tile being, of course, "slushed" at the time of laying so as to bond it to the courses of bricks constituting the facing or outer wall section. In a like manner the wall may be backed by brick as shown in Figure 13 and the inner surface of the wall may be finished by plastering or the application of a layer of concrete or other suitable material as shown in the said figure, and in this case also the step of slushing will be performed so as to provide a bond between the inner and outer wall sections. In any or all of these different methods, and in lieu of providing the steps or sockets 99 as previously described, the wall may be formed upon its inner surface with a shoulder such as indicated in Figures 12 and 13 of the drawings by the numeral 102.

In erecting a building wall by the ordinary methods of procedure, a scaffolding is constructed as the building operation continues, as previously explained, and at certain intervals in the height of the temporary scaffolding structure, platforms are arranged on which the workmen stand while laying the bricks. As a matter of economy it is customary to arrange these platforms at such an elevation that the maximum number of courses of bricks may be laid by the workmen without requiring the establishment of another platform or stage. Therefore, the workman is required, in the first instance, to bend or stoop in order to lay the first several courses of bricks and, finally, he is required to reach overhead in order to lay the final courses. This not only inconveniences the workman but, on account of the

unusual postures he is required to assume in laying the bricks, the work is liable to be performed in an unsatisfactory manner.

As the building operation progresses, it, 5 of course, becomes necessary that means be provided for supporting the workmen and their materials at different elevations and the present invention therefore contemplates the provision of brackets 103 which are provided at their upper ends with attaching 10 portions 104 adapting them to be secured to the lower flanges 16 of the mold wall members 14 as clearly shown in Figure 2 of the drawings. At their lower portions the 15 brackets are provided with triangular rests 105 upon which platform planks or boards 106 may be secured for the purpose stated. In order to properly space the lower ends of the brackets and prevent tilting thereof with 20 relation to the wall as the wall is constructed, spacing beams 107 are secured to the lower portions of the said brackets and are interposed between these portions and the inner surface of the wall. It will be understood, 25 of course, that the workman standing upon the platform thus provided may operate the lever 34 so as to elevate the platform to suit his convenience and this is a feature of decided importance for the reason that unlike 30 the conditions existing where ordinary wooden scaffolding is built, the workman may at all times lay his bricks while he is standing in the most convenient posture, being neither required to stoop nor bend nor 35 to elevate his arms above his head. As a consequence, disregarding all other advantages which attend the carrying out of the method of the present invention, a workman is enabled to lay the bricks and pour the concrete backing or supply some other backing, 40 without undue exertion and he can therefore perform his labors more expeditiously and in a more accurate manner.

By reference to Figure 10 of the drawings, 45 it will be observed that the rack bars 20 serve not only the purpose which has heretofore been ascribed to them but they likewise serve as a bonding or tying means between the sections which constitute the uprights of the skeleton frame structure so that 50 while section after section may be added to the different uprights as the building operation progresses, no interruption to the work is occasioned and considerable time is thus saved. The rack bars are, of course, dismounted from the uprights and arranged in a more elevated position as the work progresses, the bars which connect the successive 55 sections of the uprights, however, being left in place until the building operation is entirely completed.

It has been found by actual experience that a building wall erected by the method of the present invention will present a 60 smooth and attractive interior finish which

is not the case where the wall is backed by the ordinary methods and by laying tile or bricks in rear of the facing wall section. The surface of the concrete backing is, as stated, smooth and therefore will readily accommodate any finishing materials which may be applied thereto. While the backing is exceptionally substantial and presents all of the advantages which might be obtained by the erection of a concrete wall, as such, it 70 does not present the disadvantage that it is subjected to the elements, for the facing of vitreous material which is either in the form of bricks or tile, protects the backing from the elements so that moisture is not absorbed 75 and therefore the backing is not liable to crumble or disintegrate. While particular reference has been made to the use of brick as a facing material, it will be understood that various materials might be employed 80 for this purpose, such for example, as tile or split bricks, and as a matter of fact it is an important feature of the present invention that split bricks may be employed instead of whole bricks thereby effecting a very considerable saving in the cost of the materials. 85

In the foregoing description of the invention particular reference has been made to the laying of a foundation or footing as the first step of the method but this is not necessarily an important step inasmuch as in some soil conditions, the foundation might be laid without the necessity of first providing a footing. For example, as illustrated in Figure 14 of the drawings, a foot may or may not be laid and building block may be employed as the foundation material. Therefore, the uprights of the skeleton frame structure may be erected in some other manner than by being anchored to a footing. They may be driven into the ground where the soil conditions are suitable, or they may be set into concrete foundations cast in the excavation, or anchored by stakes, or in fact 100 set up and sustained by any means found appropriate. Likewise, instead of employing bonding ties such as the ties 97 previously referred to, the bricks may be laid at suitable intervals in such a manner as to provide the well known header as a bond between the 105 facing section of the wall and the backing section.

By reference to Figure 3 of the drawings it will be observed that, at the corners of the wall, the members 82 of the brick laying guide meet end to end at right angles, so that when the bricks are laid in this angle, they will be exactly squared. As a consequence, while an inexperienced person may lay the bricks, the corners of the building structure will be precisely plumb and square and in fact more accurately laid than would be possible by manual labor alone. 120

As before pointed out, the uprights which are to constitute the skeleton frame struc- 125

ture, are initially secured at their lower ends to the footing which is molded in the foundation, or are in some other manner mounted and supported at their lower ends. As the building operation progresses, the lower uprights or sections may be removed and carried upwardly with the structure thereby permitting of the employment of but comparatively few of the uprights, the uprights being, under these conditions, supported upon the completed portions of the wall by the tie bolts 101.

As before explained, the mortar between the courses of brick is pointed or struck, at the face of the wall, but this is not done at the back or inner side of the facing wall section so that a small lip of mortar will project from between each two superposed courses of brick, and when these lips set or harden, and the concrete is poured to provide the backing of the wall, the lips will become embedded in the concrete and a more intimate and firm union of the facing and backing sections of the wall will be effected.

While it is not practical to erect exterior building walls of concrete alone, for the reasons before explained, it is practical to erect interior or partition walls of this material and it will be evident therefore that the appliances embodying the present invention may be employed in carrying out this operation, it being only necessary to support upon the uprights 3 and 4, two of the mold wall members 14 arranged in opposed relation to each other and proceed with the pouring of the concrete in the manner heretofore explained.

Having thus described the invention, what is claimed as new is:—

1. The method of erecting a building wall which comprises erecting a skeleton frame structure, laying a facing wall section, arranging a mold wall member in spaced relation to said facing wall section, utilizing the said facing wall section and the mold wall member as the walls of a mold chamber in pouring a backing for the facing wall section, and tying the frame structure to the wall as the wall is constructed and thereby carrying the frame structure up with the said wall.

2. The method of erecting a building wall which comprises digging an excavation on the site on which the wall is to be erected, laying a foundation, erecting a frame structure in the excavation including plumb uprights, supporting a mold wall member upon the uprights in plumb relation to the plane of the inner face of the wall to be erected, laying a facing wall section in spaced relation to the said mold wall member, and utilizing the said facing wall section and the mold wall member as the walls of a mold chamber in laying a backing for the facing wall section.

3. In apparatus for use in the erection of a building wall, a support, and a material laying guide mounted upon the support and vertically adjustable thereon, the said guide being likewise mounted for movement outwardly from the face of the wall in the course of erection thereof.

4. In apparatus for use in the erection of a building wall, spaced uprights, and a material laying guide mounted upon the uprights and vertically adjustable thereon and supported for swinging movement to occupy a perpendicular plane and likewise to occupy a position swung away from the wall in the course of erection to permit of finishing of the surface of the wall.

5. In apparatus for use in the erection of a building wall, spaced uprights, brackets vertically adjustably mounted thereon, a material laying guide suspended for swinging movement between the brackets, means for holding the guide in position with its working side occupying a perpendicular plane, and operable likewise to hold the guide in a position swung away from the face of the wall being erected.

6. In apparatus for use in the erection of a building wall, spaced uprights, brackets mounted upon the uprights for vertical adjustment thereon, a material laying guide suspended for swinging movement between the brackets and having a plane working face against which the material is to be laid, stop members upon the said brackets, and means upon the guide for coaction with the stop members to maintain the guide in position with its working face perpendicular and in position swung away from the face of the wall.

7. In apparatus for use in the erection of a building wall, spaced uprights, brackets mounted upon the uprights for vertical adjustment therealong, bearing members mounted for adjustment upon the uprights toward and from the plane of the uprights, arms suspended from the bearings, and a material laying guide extending between the arms.

8. In apparatus for use in the erection of a building wall, spaced uprights, brackets mounted upon the uprights for vertical adjustment therealong, bearing members mounted for adjustment upon the uprights toward and from the plane of the uprights, arms suspended from the bearings, a material laying guide extending between the arms, and means for maintaining the said guide in position with its working face perpendicular and likewise in position swung away from the face of the wall.

9. In apparatus for use in the erection of a building wall, spaced uprights, a material laying guide mounted upon the uprights, and having a plane abutment face presented toward the uprights, and a mold wall mem-

- ber likewise mounted for vertical adjustment upon the uprights and having a plane mold face presented toward the plane abutment face of the guide.
- 5 10. In apparatus for use in the erection of a building wall, spaced uprights, a material laying guide mounted upon the uprights and having a plane abutment face presented toward the uprights, and a mold wall member likewise mounted for vertical adjustment upon the uprights and having a plane mold face presented toward the plane abutment face of the guide, the said guide and mold wall member being independently adjustable.
- 10 15. In apparatus for use in the erection of a building wall, a supporting structure, a material laying guide vertically adjustable upon the structure, and a mold wall member likewise vertically adjustable upon the structure, the said guide and mold wall member having opposing plane faces.
- 20 12. In apparatus for use in the erection of a building wall, spaced uprights, a mold wall member extending between the uprights and supported thereby for vertical adjustment, and a material laying guide supported between the uprights in opposition to the mold wall member.
- 25 30. 13. In apparatus for use in the erection of a building wall, spaced uprights each comprising sections disposed in vertical alinement, rack bars mounted upon and secured to the sections of the uprights and constituting a means for connecting the sections together in their vertically alined relation, a material confining member vertically adjustably mounted upon the uprights, and means upon the guide for coaction with the rack to support the guide at various elevations.
- 35 40. 14. In apparatus for use in the erection of a building wall, spaced uprights, a mold wall member vertically adjustably mounted upon the uprights, spacing means working between the said mold wall member and the faces of the uprights to hold the mold wall member in perpendicular relation during the molding operation, the said spacing means being displaceable subsequent to completion of the molding operation, whereby to permit of slight displacement of the said mold wall member with relation to the face of the material which has been molded.
- 45 50. 15. In apparatus for use in the erection of a building wall, spaced uprights, a mold wall member vertically adjustably mounted upon the uprights, wedges operating between the mold wall member and the faces of the uprights, and means for adjusting the wedges.
- 55 60. 16. In apparatus for use in the erection of a building wall, a temporary frame structure comprising corner and intermediate uprights, mold wall members vertically adjust-
- able upon the said uprights and extending between the same, material laying guides mounted upon the uprights and vertically adjustable thereon and opposing the said mold wall members, the said members at 70 their adjacent ends meeting at a right angle and the said material laying guides likewise meeting at their relatively adjacent ends at a right angle, and scaffolding supporting brackets mounted upon the said 75 mold wall members.
- 70 75. 17. In apparatus for use in the erection of a building wall, spaced uprights, rack bars upon the uprights, a mold wall member extending between the uprights, and manually operable jacking means mounted upon the said mold wall member and coacting with the rack bars and operable to effect vertical adjustment of the said mold wall member upon the said uprights.
- 80 85. 18. The method of erecting a building wall which comprises the steps of erecting a temporary supporting structure, supporting upon the structure in plumb and level position a guide, laying facing bricks or the like against the guide to provide an outer facing wall section, arranging a mold wall upon the said structure in spaced relation to the inner side of the said facing wall section, and establishing a backing for the facing wall section by pouring concrete into the space between the said facing wall section and the mold wall.
- 90 95. 19. The method of erecting a building wall which comprises the steps of erecting a temporary supporting structure, supporting upon the structure in plumb and level position a guide, laying facing bricks or the like against the guide to provide an outer facing wall section, arranging a mold wall upon the said structure in spaced relation to the inner side of the said facing wall section, establishing a backing for the facing wall section by pouring concrete into the space between the said facing wall section and the mold wall, displacing the mold wall with relation to the molded mass of backing material after the said mass has partly set and then adjusting the said mold wall upwardly to a new position of adjustment, and continuing the operation.
- 100 105. 110. 115. 20. The method of erecting a building wall which comprises the steps of making an excavation on the site where the structure is to be erected, laying a footing of plastic material in the excavation, erecting uprights upon the footing, connecting the uprights by ties adjustable to permit of each upright to assume a true plumb position, disposing a mold wall upon the uprights, 120 pouring material between said mold wall and the wall of the excavation to provide the foundation of the wall structure, adjusting the mold wall to different elevations as the pouring operation continues, until the 125 130

foundation has been completed, associating with the uprights a material laying guide in position opposing the said mold wall member, laying facing material against the 5 said guide, and employing the facing material and the said mold wall as the walls of a mold chamber and pouring backing material into said chamber to set and harden, and continuing the operation.

10 21. The method of erecting a building wall which comprises erecting a skeleton frame structure including uprights formed in sections, laying a facing wall section, arranging a mold wall member in spaced rela-

tion to said facing wall section, utilizing the 15 said facing wall section and the mold wall member as the walls of a mold chamber in pouring a backing for the facing wall section, tying the said uprights to the wall as the laying of the wall progresses, connecting the upright sections to one another, and removing the lower sections and employing them as upper sections as the operation progresses.

20 In testimony whereof I affix my signature.

FRANK R. EVANS. [L. S.]
